UNITED STATES PATENT OFFICE.

ERNST GEORG SCHMIDT, OF DUSSELDORF, GERMANY, ASSIGNOR TO RHEINISCHE METALLWAAREN- UND MASCHINENFABRIK, OF DUSSELDORF- DERENDORF, GERMANY, A CORPORATION OF GERMANY.

DEVICE FOR MANIPULATING GUN-TRIGGERS.

1,147,556.

Specification of Letters Patent.

Patented July 20, 1915.

Application filed November 27, 1914. Serial No. 874,302.

To all whom it may concern:

Be it known that I, ERNST GEORG SCHMIDT, engineer, a subject of the German Emperor, residing at 84 Winkelsfelderstrasse, 5 Dusseldorf, Germany, have invented certain new and useful Improvements in Devices for Manipulating Gun-Triggers; and I do hereby declare the following to be a full, 10 clear, and exact description of the invention, such as will enable others skilled in the art to which it appertains to make and use the same.

The invention relates to a device for manipulating gun triggers by means of cables 15 such as Bowden cables.

The object of the invention is to enable the trigger to be drawn from several places and for that purpose the trigger is under the influence of a piece connected in a special 20 manner with a plurality of cables adapted to be drawn independently of each other.

An embodiment of the invention is represented on the accompanying drawing in which—

25 Figure 1 is a plan view of a gun breech provided with a device according to the invention. Fig. 2 is a section through a device constructed according to my invention in the position of rest. Fig. 3 is a similar section 30 in the position of the parts after having drawn one of the cables.

As the construction of the trigger is of no importance for the invention, it is not shown in the accompanying drawing. It may be a 35 spring trigger of any known construction which is operated by a lever *b* pivotally mounted on the gun breech *a*. In the position of rest a spring pin *c* movable within a sleeve *e* fastened on the cradle *d* rests 40 against the trigger lever *b* and is in engagement with a bell crank lever *f*.

Within a casing *h* fastened to the cradle a pin *g* is lengthwise movable and held in its position of rest by means of a spring *i*. The 45 pin *g* is provided at one end with a hook *k* for engaging the bell-crank lever *f*, and at its other end with a disk or piston *l* lying

within an enlargement *m* of the casing *h*. The disk or piston *l* is provided with a plurality of holes through which headed Bowden-cables *n* are loosely passed in such manner that by drawing one of the Bowden-cables the disk or piston *l* is moved from the position shown in Fig. 2 to the position shown in Fig. 3, the other Bowden-cables retaining 55 their original position. By the said movement of the piston or disk *l* the pin *g* is moved longitudinally and thereby the bell crank lever *f* is rocked so as to press the pin *c* in the direction against the trigger lever *b* 60 whereby the latter is moved so as to fire the gun. When the drawn Bowden-cable is loosened the spring *i* returns the pin *g* and the disk *l* into their original position so that after the trigger has again been put under 65 tension the gun can again be fired by drawing any one of the Bowden-cables.

It is self evident that the several Bowden-cables may be led to different places, so that the gun can be fired from any desired 70 place.

The plurality of Bowden-cables may be connected immediately with the pin *c* without departing from the spirit of the invention.

Having thus described my invention what I claim is:

In a device for manipulating gun triggers, the combination of a trigger lever, a member engaging the trigger lever, means 80 for operating such member comprising a bell-crank lever, a sliding pin engaging said bell-crank lever, a spring acting on said pin, a piston-like disk to which said pin is connected having a plurality of holes therein, 85 and headed cables loosely passed through said holes.

In testimony whereof, I have signed this specification in the presence of two subscribing witnesses.

ERNST GEORG SCHMIDT. [L. s.]
